CUTTING OR CLEAVING OF SLABS

Axel Richard Lundquist, Norrkoping, Sweden

Application March 11, 1948, Serial No. 14,193
In Sweden March 31, 1947

2 Claims. (Cl. 125—13)

1

The present invention relates to the cutting or cleaving of slabs, particularly marble or lime slabs adapted to be used for coating walls or ceilings. One object of the invention is to facilitate attaching of the slabs to the base by providing the back of the slab with a ridge serving to hold the slab at said base. A further object of the invention is to produce such a slab from a blank or work-piece of substantially double the thickness of the finished slab and to saw said blank edge-wise from two opposite sides so as to leave a narrow non-sawn portion at the centre or middle part of the slab, whereupon the blank is broken into two parts, so that two slabs are produced each having a ridge extending across the back of the slab. It is further the object of the invention to provide a machine for the performance of said method.

One embodiment of the invention will be described with reference to the accompanying drawings, in which

Figure 1 shows a side elevation of a machine according to the invention.

Figure 2 is a top view of the machine shown in Figure 1.

Figure 3 is a side view of the machine shown in Figures 1 and 2 seen from the left side of Figure 1.

Figure 4 is a slab partly sawn through and shown in section at a certain stage of its production process, and

Figure 5 one of the broken off slabs seen from its back.

When carrying out the method according to the invention a slab of the material in question (for instance marble or lime stone) is first cut or sawn so as to obtain a thickness slightly exceeding the double thickness of the final slab to be produced. This thick slab is placed edge-wise and sawn through from two opposite ends as will be seen from Figure 4. In this figure the slab is designated by 36, and the grooves 37 and 38 sawn in from two opposite ends are so deep that at the centre of the slab 36 there is left a ridge 39 not being sawn through and having a suitable width in order to allow the two halves of the slab easily to be broken into two at this place. After the grooves 37 and 38 have been made in the slab 36, it is broken into two parts, so that two slabs are obtained, each having at its back a ridge with a more or less rugged surface of fracture, said ridge being the remainder of the portion 39 not sawn through. Figure 5 shows such a final "half" slab seen from its back. The slab is designated by 36 and the said ridge by 40. The ridge 40 makes the

slab highly suitable for the attachment in plastering or any other base, as the ridge has an uneven surface of fracture and thus well adheres to this base and prevents the slab from loosening. Hitherto this problem caused considerable difficulties as regards marble and lime slabs.

Figures 1 to 3 show one embodiment of a machine adapted for carrying out said method. The machine comprises supports or stands 2 carrying two rails or guide bars 3. A carriage 4 with wheels may be moved along the rails 3. Between the rails 3 there is a rack 34, adapted to be engaged by a pinion 35 mounted in the carriage 4. By means of a gear transmission 31, 32 the pinion 35 meshes with a hand wheel 30. Rotation of the hand wheel 30 thus causes the carriage 4 to be displaced along the rails 3. The carriage 4 is provided with ribs or bars 6 placed sparsely so as to leave spaces 7 there-between. By this arrangement it is possible to fix various devices at the carriage.

In the present case two logs 8 and a horizontal U-shaped beam 13 are attached at top of the carriage 4. The ends of the logs 8 turned to the U-beam are recessed so as to receive a board 11 or the like. Wedges 12 may be inserted between the board 11 and the abutments formed by the recesses of the logs 8. The slabs 9 to be cut are placed edge-wise in a row between the U-beam 13 and the board 11, the wedges 12 then being inserted as described so as to fix the slabs 9 safely in their places. As will be seen from Figure 2 the board 11 lies at such a level relative to the ribs or bars 6, on which the lower edges of the slabs 9 rest, that the board will be pressed against the central or middle part of the slabs 9.

The machine also has a frame or support 1 carrying an arm 29, into which there is threaded a screw 26 (see especially Figure 2). At its upper end the screw 26 is provided with a hand wheel 27. The lower end of the screw is mounted in another arm 28 in such a way that, when the screw is rotated, the arm will be raised or lowered in relation to the support 1. The arm 28 is controlled by guides attached to the arm 29. The arm 28 is provided with two bearings 17, in which a shaft 15 is journalled. At one end this shaft 15 carries a saw blade 14 and at its other end a belt pulley 18. A protecting cover 16 is arranged over the saw blade 14. The longitudinal position of the saw blade 14 is adjusted in such a manner that it lies in a vertical plane dividing the slabs 9 into two equal parts.

Fixed to the support 1 is a bar 24 the upper end 55 of which 1 carries a lever 22 which is swingably

mounted by means of a bearing 23. At one end of the lever 22 there is mounted a motor 21 provided with a belt pulley 20. The pulley 20 is placed substantially vertically above the pulley 18. A belt 19 runs across the two pulleys. The other end of lever 22 is loaded with a weight 25, the belt 19 in this way always being tense independently of the temporary level of the pulley 18.

The arrangement operates in the following way: After the slabs 9 have been clamped between the board 11 and the beam 13 in the manner described hereinbefore (which ought to take place when the carriage 4 is in its right hand end position) the saw blade 14 is lowered by operating the hand wheel 27 so that the lower end of said saw blade will be located slightly above the central line of the slabs 9. After the circular saw blade 14 has been brought into rotation by the motor 20, the carriage is moved to the left by operating the hand wheel 39, and the saw blade 14 will then saw a groove into the slabs 9. When all slabs 9 have passed under the saw blade 14 the carriage 4 is returned to its initial position, and all slabs are turned round, so that their other side is turned upwards. Then the carriage is again moved to the left and a groove will now be cut into the side of the slabs 9 now turned upwards. When this operation has been finished, the slabs 9 now having the appearance shown in Figure 4 are removed. Finally, the slabs 9 are broken into two halves at their central ridge 39, so that two slabs provided with a ridge 40 are obtained of each slab 9.

Though the invention has hereinbefore been described in connection with a certain embodiment of same, it is obvious that the invention includes a number of modifications within the scope of the claims.

What I claim is:

1. Process of producing very thin slabs comprising the steps of forming from appropriate building material a thin slab-shaped element having opposite flat surfaces and opposite narrow edge faces; sawing into said thin slab-shaped element edgewise from said opposite narrow edge faces so as to leave a narrow non-sawn central portion of said thin slab-shaped element; supporting during said sawing said thin slab-shaped element in transversal direction normal to the plane of the sawing and from said opposite flat

35

50

surfaces of said thin slab-shaped element only along said narrow non-sawn central portion of said thin slab-shaped element; and breaking thereafter said narrow non-sawn central portion of said thin slab-shaped element so as to obtain two very thin slabs, each having a ridge extending across one of said flat surfaces of said very thin slabs and being the remainder of said narrow non-sawn central portion of said thin slab-shaped element.

2. Process of producing very thin slabs comprising the steps of forming from appropriate building material a thin slab-shaped element having opposite flat surfaces and opposite narrow edge faces; sawing into said thin slab-shaped element edgewise from said opposite narrow edge faces so as to leave a narrow non-sawn central portion of said thin slab-shaped element; pressing during said sawing in transversal direction normal to the plane of sawing against said opposite flat surfaces of said thin slab-shaped element only along said narrow non-sawn central portion thereof so as to support during sawing said thin slab-shaped element from said opposite flat surfaces thereof only along said narrow non-sawn central portion of said thin slab-shaped element; and breaking thereafter said narrow non-sawn central portion of said thin slab-shaped element so as to obtain two very thin slabs, each having a ridge extending across one of said flat surfaces of said very thin slabs and being the remainder of said narrow non-sawn central portion of said thin slab-shaped element.
